CLAIM

The ornamental design for a computer keyboard or similar article, as shown and described.

DESCRIPTION

FIG. 1 is a top plan view of a computer keyboard or similar article showing our new design;
FIG. 2 is a front elevational view thereof on a reduced scale;
FIG. 3 is an end elevational view thereof on a reduced scale;
FIG. 4 is a rear elevational view thereof on a reduced scale;
FIG. 5 is an elevational view of the end opposite that shown in FIG. 3, also on a reduced scale, and
FIG. 6 is a bottom plan view thereof on a reduced scale.

FIG. I

FIG. 2
